DESIGN FOR A FLASK

Frank E. Ball, Muncie, Ind., assignor to Ball
Brothers Company, Muncie, Ind.

Application November 12, 1934, Serial No. 53,978

Term of patent 14 years

To all whom it may concern:

Be it known that I, Frank E. Ball, a citizen of the United States, residing at Muncie, in the county of Delaware and State of Indiana, have invented a new, original, and ornamental Design for a Flask, of which the following is a specification, reference being had to the accompanying drawing, described forming part thereof.

In the accompanying drawing:

Figure 1 is a front elevation;
Figure 2 is a side elevation, both sides of the flask being alike; and
Figure 3 is a bottom plan view.

I claim:

The ornamental design for a flask as shown and described.

FRANK E. BALL.
